UNITED STATES PATENT OFFICE.

ANE P. SCHAT, OF THE HAGUE, NETHERLANDS.

DAVIT.

Application filed December 26, 1919. Serial No. 347,638.

To all whom it may concern:

Be it known that I, ANE P. SCHAT, a citizen of Holland, residing at The Hague, in the Province of Zuid, Netherlands, and 5 Kingdom of the Netherlands, have invented certain new and useful Improvements in Davits, of which the following is a specification.

For lowering a lifeboat the rope or fall of 10 the boat is often passed around a toggle or a bollard and then veered by hand; it is well known, however, that should the mate let the fall slip, a disaster is practically inevitable. Another method of lowering a boat consists 15 in that the fall runs directly from the davit to a fall drum provided with a band-brake, but a band-brake has the unfortunate feature that the presence of water or oil between the band and the brake disc may cause the heavy 20 boat to plump down notwithstanding the utmost efforts of the brakeman.

The object of my present invention is to 25 provide improved means by which the lowering of heavy loads such as lifeboats may be effected with greater safety than heretofore. With this main object in view the rope or fall is secured to the drum of a hoisting apparatus and between the load and said drum passed over one or a plurality of friction 30 surfaces which during the unwinding operation are, or may be, prevented from turning in the direction of the rope. It will be understood that with these means the tension of the rope or fall is almost entirely taken 35 up by said friction surfaces, whereby the hoisting apparatus is released from any considerable strain during the lowering operation.

In case the hoisting apparatus is actuated 40 by a worm meshing with a worm wheel on the fall-drum, said worm is preferably made to act selfbraking. With such a self-braking worm the mate may safely release the handle during the lowering operation without the 45 load falling. Owing to the fact that during the lowering of the boat, the fall-drum, and consequently also the self-braking worm, have to take up only an insignificant part of the load, my invention allows of the provision of means whereby the shaft of the 50 worm is driven with increased rotary speed from a suitable driving shaft so that lowering may be effected very quickly. The said fact also permits of making the worm non-self-braking and of providing the shaft of the worm with an ordinary band brake or

the like for controlling the lowering speed, as a very small braking power here suffices for instantly stopping the descending boat.

It should be noticed that both falls of the 60 one boat may be wound on one and the same drum whereby inequality between the lowering speeds of said falls is obviated; the same effect may be realized by winding the said falls on individual drums actuated by common driving means.

The friction surfaces between the boat and the hoisting apparatus are preferably made so as to have freedom of rotation in the direction of motion of the fall during the 70 hoisting operation but to remain stationary when the rope passing over the same is unwound. If desired, however, these friction surfaces may be allowed to follow the movement of the rope during the lowering operation. 75

In the annexed drawing, Fig. 1 illustrates a front elevational view of a lifeboat, and Fig. 2 a plan view of part of said boat which, in both cases, is coupled with my improvements. 80

The boat 1 is suspended from a davit 3 by means of a rope or fall 2. Said rope is associated with the drum 4 of a winch, and intermediate between said drum and the davit 3 passed around a bollard 5 which here constitutes the friction surface mentioned hereinbefore. The said bollard has freedom of rotary motion in the direction of the arrow shown, but a suitable ratchet mechanism 5^a 85 prevents it from turning in the reverse direction. It will be readily understood that the bollard 5 does not offer any noticeable resistance against the winding of the rope, but that it takes up a considerable part of the 90 strain during the lowering operation, when it is held stationary by the ratchet gear 5^a.

Secured to the drum 4 is a worm wheel meshing with a worm 7 which, in the embodiment illustrated, is of the self-braking 100 type. Keyed to the spindle 8 of the worm is a gear 9, and also a pinion 10 which, in the position shown in Fig. 1, meshes with a gear wheel 11. The said gear 11 is secured on a sleeve 13 which carries a pinion 12, and 105 which is slidably but non-rotatably mounted on a shaft 14. The pinion 12 meshes with a gear 15 on a shaft 16 which as well as shaft 14, is provided with a square end for receiving a suitable operating handle. 110

The arrangement is such that an axial displacement of the sleeve 13 through a certain

distance causes the pinion to mesh with gear 9 and the pinion 10 to disengage the gear 11.

When it is required for the boat to be lowered, the sleeve 13 is moved into the position shown in Fig. 3, and the operating handle placed on shaft 16. If now the handle is turned the speed of shaft 14 is geared up, whereby the worm 7 rotates at increased speed and the fall is unwound very quickly. By placing the handle on the intermediate shaft 14 the gearing up may be reduced.

For hoisting the boat the pinion 12 is brought into position to mesh with gear 9, and the operating handle put on shaft 14, whereby the rotary speed of the driving shaft is geared down before being transmitted to the worm 7. If the falls are unloaded the speed of the driving shaft may be geared up also during the lowering operation.

The davits shown in the drawings are inclined toward the water to cause them to swing outboard automatically, as is the case with the davits shown in my pending applications, #390,603, #286,018, #259,790, and #347,637; but it will be understood that the device works well with any automatic davit, and also with non-automatic davits. With the former it controls the rotary movement of the davit in both directions—inboard and outboard—while with the latter it is good for hauling in the boat.

But attention is called to the fact that my device is specially useful with automatic davits, because of the special difficulty experienced with this class of davits in controlling their rotary outboard movement under the greatly varying conditions of load, etc., which movement is in a substantially horizontal direction, and therefore calculated to subject the davit and operating mechanism connected therewith to objectionable lateral strains, and is often an occasion of danger to passengers in the boat.

Of all automatic davits, the inclined davits are hardest to control in their rotary outboard movement, because the rocking and listing of the ship causes great variations in the inclination of the davit, and correspondingly great variations in its rotatable tendency under different conditions.

It will be seen that my arrangement gives such a light strain on the operating mechanism connected with the drum, that a fully loaded boat can be easily set overboard with great evenness and regularity of movement, in a manner altogether satisfactory.

Having now described my invention, what I claim as new and desire to protect by Letters Patent is—

1. In a device of the character described, a davit having a rope; a boat connected to

the outer end thereof; a drum for the hauling end of the rope; and a member supported on the deck of the ship at a point in the path of the rope between the davit and the drum, said member having a friction surface with the hauling part of the rope passed around said surface and held in frictional engagement therewith by the tension in the rope, said member having freedom of rotation in the direction of the travel of the rope when the rope is wound upon the drum, and having means for locking it against rotation in the opposite direction; whereby to automatically introduce frictional resistance in the part of the rope between the davit and the drum during the outward movement of the rope from the drum, and to permit the free movement of the rope as it is wound upon the drum.

2. In a device of the character described, a lifeboat; a davit rotatable on its longitudinal axis to inboard and outboard position, and having a rope for engaging the lifeboat; a drum for the hauling end of the rope; and a member supported on the deck of the ship at a point in the rope between the davit and the drum, and having a friction surface with the hauling part of the rope passed around said surface and held in frictional engagement therewith by the tension in the rope, said member having freedom of rotation in the direction of travel of the rope when the rope is wound upon the drum to raise the boat and swing the davit inboard and having means for locking it against rotation in the opposite direction.

3. In a device of the character described, a lifeboat and a davit for handling the boat, said davit being movable to inboard and outboard position, and having a rope connected at its outer end to the boat; a drum at the inner end of the rope for hauling in and paying out the rope, to control the movements of the davit and the boat; and means automatically operable for reducing the strain of the load on the drum as the rope is paid out thereby.

4. In a device of the character described, a davit movable to inboard and outboard position, and biased to swing outboard; a rope for the davit; a boat connected to the outer end of the rope; a self-braking drum at the inner end of the rope for hauling in and paying out the rope to control the movements of the davit and of the boat; and means automatically operable for reducing the strain of the load on the drum proportionate to the weight of the load, as the rope is paid out by the drum.

In testimony whereof I affix my signature.

ANE P. SCHAT.
